D 5695

5,695

UNITED STATES PATENT OFFICE.

WILLIAM BURLINGHAM, OF NEW YORK, N. Y.

DESIGN FOR A PUMP.

Specification forming part of Design No. 5,695, dated March 19, 1872.

SPECIFICATION.

To all whom it may concern:

Be it known that I, WILLIAM BURLINGHAM, of the city, county, and State of New York, have originated a new Design for Pump-Stocks, of which the following is a full, clear, and exact description, reference being had to the accompanying photographic illustration making a part of this specification.

A in the photograph represents a square pedestal or base. B is a round section or portion next above A. C is a flat-sided ball at or near the center of the pump. D is a round section or portion similar to B, and next above

C. E is an octagonal section or portion next above D, and at the top of the pump surmounted by a cap.

This I consider a neat and tasteful shape for a pump-stock, the above described combination of forms imparting an elegant finish.

What I claim as my invention, and desire to secure by Letters Patent, is—

The design for pump-stocks herein set forth.
WILLIAM BURLINGHAM.

Witnesses:

THOS. PARISH SHERMAN,
NELSON MERRILL.
